CLAIM

The ornamental design for a reversible tent top baby seat cover throw, as shown and described.

DESCRIPTION

FIG. 1 is a perspective view of the reversible tent top baby seat cover throw showing my new design;

FIG. 2 is a front elevational view thereof;

FIG. 3 is a top plan view thereof; and,

FIG. 4 is a perspective view thereof with the head end folded over.

The broken lines showing the handle in FIGS. 1 and 2 and the baby with the baby carrier in FIG. 4 are for illustrative purposes only and forms no part of the claim design.
